UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 27,070, dated May 18, 1897.

Application filed March 27, 1897. Serial No. 629,624. Term of patent 3½ years.

To all whom it may concern:

Be it known that I, HARRISON H. ROUNTREE, a citizen of the United States, and a resident of Chicago, in the county of Cook and State of Illinois, have invented and produced a new and original Design for Sprocket-Wheel and Driving-Chain Guards or Shields for Bicycles, of which the following is a specification.

In the accompanying drawings, Figure 1 is a perspective view of a guard embodying my design, and Fig. 2 is a transverse section on the line 2 2 of Fig. 1.

The essential features of this design embrace a continuous flanged margin comprising two substantially parallel longitudinal members of unequal length connected at front by a semicircular member and at rear by a diagonally-disposed member extending from the end of the longer upper longitudinal member to the end of the shorter longitudinal member in the form of an ogee curve.

A guard or shield of my design consists of a marginal frame the edges of which are continuous and unbroken and which comprises straight and substantially parallel upper and lower sides a a' , and a front circular side a^2 , which forms a continuation of and joins the

upper and lower sides a a' . The upper side a of said marginal frame is longer than, and the rear end thereof extends beyond, the rear end 30 of the lower side a' , and the rear extremities thereof are connected by a rear side piece a^3 , which forms an ogee curve.

A guard or shield of my design also comprises a flange a^3 , which projects laterally 35 from the edge of the upper and front sides a and a' of the marginal frame, so that it will extend over the driving-chain when said guard or shield is applied to a bicycle. The space within the marginal frame is occupied 40 by a web of open-work a^4 .

I claim—

The design for a sprocket-wheel and driving-chain guard or shield for bicycles, substantially as herein shown and described. 45

In testimony that I claim the foregoing as my invention I hereunto set my hand, this 20th day of March, 1897, in the presence of two witnesses.

HARRISON H. ROUNTREE.
